UNITED STATES PATENT OFFICE.

BERNHARD TEUFER, OF CHEMNITZ, GERMANY.

APPARATUS FOR DYEING THREAD AND LIKE MATERIAL.

1,074,390.

Specification of Letters Patent. Patented Sept. 30, 1913.

Application filed October 29, 1912. Serial No. 728,340.

To all whom it may concern:

Be it known that I, BERNHARD TEUFER, a subject of the King of Saxony, residing at Chemnitz, Saxony, Germany, have invented 5 an Improvement in Apparatus for Dyeing Thread and like Material, of which the following is a specification.

This invention relates to an apparatus for dyeing various materials, particularly skeins 10 of silk, woolen, linen or other threads.

I am aware that heretofore skeins of threads have been placed upon reels and passed through a bath of dyeing material by means of endless chains, in which apparatus the reels upon which the thread is wound have also been caused to turn during 15 the passage of the thread through a bath.

I am also aware that it is not new to pass the skeins of threads through several baths, 20 first, through the bath of dyeing material and then through baths of various substances for cleansing the threads after having been dyed.

The object of my present invention, how- 25 ever, is the production of an apparatus for dyeing skeins of various threads, in which the thread to be dyed is passed slowly and successively through baths in which the liquid is caused to move in the opposite di- 30 rection to that in which the thread is con-veyed, one in which the reels upon which the skeins of thread are placed are turned in the direction so that the forward side of the reel has an ascending motion and the 35 rearward side of the reel has a descending motion, and one in which the reels carrying the threads to be dyed are only sub-merged to their axes in passing through the baths, the motion imparted to the reel 40 being rapid, so that a thorough immersion of the thread is effected, and, as hereinbefore stated, the baths are caused to flow in the opposite direction to that in which the reels are moved in their travel through the baths, 45 so that the thread first comes into contact with a liquid in the dyeing bath which has been more or less utilized, and it is pro-50 gressively advanced to that portion of the bath to which the freshly prepared dyeing liquid is supplied, so that an economical use of the dyeing bath is also obtained.

In carrying out my invention, I also em- 55 ploy a series of baths through which the thread is passed for cleansing the same after it has been removed from the bath contain- 60 ing the dye, all of which will be herein- 65 after more particularly described.

In the drawing, Figure 1 is a side elevation of the apparatus comprising my present invention. Fig. 2 is a plan of the same. 60 Fig. 3 is a cross section on line A A, Fig. 1. Fig. 4 is an elevation and partial cross section on an enlarged scale illustrating the reel upon which the thread to be dyed is placed, and the parts associated with the 65 reel. Fig. 5 is a plan view of the part shown in Fig. 4. Fig. 6 is an end elevation of the parts as shown in Figs. 4 and 5. Fig. 7 is an elevation of the gears by which the reels are turned. Fig. 8 is a cross section illustrating the bushings in which the inner ends of the reel shafts are journaled. Fig. 9 is an end elevation of the same, Fig. 10 is an elevation and partial cross section illustrating the manner in which the reels, 70 with the skeins of thread thereon, are im- 75 mersed in the baths as the same pass through the apparatus, and Fig. 11 is a central longitudinal section of the apparatus comprising my present invention. 80

Referring to the drawing, it will be seen that my improved apparatus for dyeing skeins of thread and like material preferably comprises a frame consisting of a base indicated at 18, and a plurality of posts or 85 uprights indicated at 1. Within this frame are placed a number of tanks. In the drawing I have illustrated three such tanks and the same are indicated at 2, 3 and 4. The tank 2 is the tank for containing the dyeing 90 liquid, and the tanks 3 and 4 are adapted to contain the rinsing and cleansing liquids. The tanks 2 and 3 are preferably in the lower portion of the frame and on the same level with each other, while the tank 4 is in 95 the upper portion of the frame above the other tanks.

Suitably mounted in the frame adjacent to the ends thereof are sprocket wheels Z³ mounted in pairs at opposite ends of the 100 apparatus. Over these sprocket wheels Z³, and also over suitable intermediate guide wheels, endless chains K are passed. The sprocket wheels Z³, at the left-hand end of the apparatus, are mounted upon a shaft 19, 105 on one end of which is also mounted a worm wheel Z². Meshing with the worm wheel Z² is a worm Z' fixed on the shaft 20, which is turned by a pulley S driven from any suitable source of power. I also employ a plu- 110 rality of reel frames each comprising end members 21, and longitudinal or connecting members 5. The end members 21 of these reel frames are pivotally connected to cor-

responding links of the endless chains K, as indicated at 22, and centrally each reel frame is provided with a transverse member 6. A short shaft 23 is connected to the end members of each of the reel frames, preferably in alinement with the point in which the same is pivotally connected with the endless chains. On each of these shafts 23 is a gear Z⁶ adapted to mesh with the teeth of a rack Z⁷ supported by the frame of the apparatus. Connected to each gear Z⁶ is an internal gear Z⁸. Each gear Z⁶ is provided with a hub indicated at 24, and on each one of these hubs 24 is mounted a journal gear Z⁴. Centrally at one end each journal gear Z⁴ is provided with a square opening, the purpose of which will be hereinafter described.

Intermediate of each internal gear Z⁸ and journal gears Z⁴ is a gear Z⁸ adapted to mesh with both the journal gears Z⁴ and the internal gears Z⁸.

The central transverse member 6 of each reel frame is fitted with a bearing 7. In each bearing 7 is a pair of bushings 9, the adjacent closed ends of which abut against one another within the bearing 7 and are locked in position therein by means of suitable pins 15 which pass through the bearings 7 and into circumferential recesses provided therefor in the outer surfaces of the bushings 9. Within each bushing 9 and movably longitudinal therein is a hollow shaft 10. Each hollow shaft 10 is suitably slotted to receive pins 15, so that the hollow shafts may be moved longitudinally of the bushing and caused to rotate therewith. At the end of each hollow shaft 10 is a flange 11 having a spherical face and being provided centrally with a square opening 12. Extending between the inner end of the bushing 9 and the outer end of each hollow shaft 10 is a spring 13, by means of which, as will be understood, the parts of this bearing and its bushings are normally maintained in the positions as illustrated in Fig. 8.

I also employ a plurality of reels, each consisting of a shaft 17, side members 25 suitably secured to the shaft 17, and reel rods H extending between the side members 25. These reel rods, as will be understood, are spaced at suitable points in the circumference of a circle. Both ends of each reel shaft 17 is preferably square, one end being adapted to pass and fit within the opening provided therefor, as hereinbefore stated, in the journal gear Z⁴, this opening being provided in that portion of the gear which passes through the plate 16 inclosing the internal gear Z⁸. The opposite end of each reel shaft 17 is adapted to pass and fit within the opening 12 provided therefor in the disk 11 on any of the hollow shafts 10, it being understood that the reels are removable and interchangeable, and that any reel may be in-

serted in any frame by placing one end of the reel shaft in the opening in the journal gears Z⁴ and moving inwardly the corresponding hollow shaft 10 against the action of its spring 13, permitting the opposite end of the reel shaft to pass into the opening 12, when the disk and hollow shaft 10 are released.

From the foregoing description, it will be apparent that in the operation of the apparatus, the material to be dyed having first been placed on the reels and the reels fixed in the reel frames, each reel will be revolved by the motion transmitted thereto from the gear wheel Z⁹, which is turned by passing over the rack Z⁷, the internal gear Z⁸ turning with the gear Z⁶, the intermediate gear Z⁸ turned by the internal gear Z⁸, and the journal gear Z⁴ which is turned by the gear Z⁸, and furthermore it is to be observed that each wheel is rotated so that its forward part is ascending and its rearward part descending during its travel through the apparatus.

In the operation of the apparatus, the reels are inserted and removed from the reel frames at the place indicated at X, Fig. 1. The reel upon being inserted in its place is caused to travel by the endless chains first downwardly and then forwardly with its axis at about the level of the dyeing liquid in the tank or vat 2 until the wheels have traveled forward through this tank 2.

I employ suitable guide rolls, indicated at Z⁹, Z¹⁰, and Z¹¹, whereby the reel frames and reels are lifted from the tank 2 and then caused to enter the tank 3, in which may be placed any suitable liquid for rinsing the threads on the reels after the same have been dyed. The reels, after passing through the tank 3, are carried upwardly and then returned by the endless chains through the tank 4 which may contain a soapy solution or any other substance adapted to cleanse the threads which have been dyed, and as will be understood, upon returning to the point X the reels with the threads thus treated are removed from the apparatus, and at all times during the horizontal travel of the reel frames and reels through the apparatus, the reels are revolved at a relatively high speed, so that a thorough immersion and consequent uniform dyeing and cleansing of the fabric is effected.

Furthermore, as hereinbefore indicated, the liquid in all the tanks is by suitable means not shown caused to flow in the opposite direction from that in which the chains, reel frames and reels travel. The object of this is to cause the material to be treated to first come in contact in any of the tanks with the bath therein which has been more or less utilized at the time the material to be treated is first immersed, and in its subsequent progress through each bath, the mate-

rial to be treated is constantly brought into a portion of the bath nearer the point of supply, at which, of course, the bath is freshest and therefore the most effective.

5 The gearing, as illustrated, will cause the reels to revolve at approximately six times the speed at which the gear wheels Z^6 are turned, but as will be understood, the speed at which the wheels are caused to revolve is 10 a matter of design and forms no part of my invention.

I claim as my invention:

1. An apparatus for dyeing threads and the like, comprising a base, a frame, a dye 15 tank, endless chains, means for actuating the same, a frame pivotally connected to the said endless chains, a device removably connected to the last aforesaid frame and adapted to support the material to be dyed, and 20 means whereby in the travel of the chains and frame the said device is turned in such a direction that its forward side ascends and its rearward side descends.

2. An apparatus for dyeing threads and 25 the like, comprising a base, a frame, a dye tank, endless chains, means for actuating the same, a frame pivotally connected to the endless chains, a device for supporting the material to be dyed, means whereby said 30 device is removably connected to the last aforesaid frame, and means whereby in the travel of the chains and frame the said device is turned in such a direction that its forward side ascends and its rearward end 35 descends.

3. An apparatus for dyeing threads and the like, comprising a base, a frame, a dye tank in the said frame, endless chains, means for driving the same in unison, a reel frame 40 pivotally connected to corresponding links of the endless chains, a reel for supporting the material to be dyed, means for removably connecting the said reel to the reel frame, and means whereby in the travel 45 of the chains and reel frame the said reel is so turned that its forward portion ascends and its rearward portion descends.

4. An apparatus for dyeing threads and the like, comprising a base, a frame, a dye 50 tank in the said frame, endless chains, means for driving the same in unison, a reel frame pivotally connected to corresponding links of the endless chains, a reel for supporting the material to be dyed, a gear associated 55 with one end of the said reel frame, a rack meshing with the said gear, a journal gear in which one end of the reel shaft is removably connected, a bearing in which the opposite end of the reel shaft is removably journaled, and means whereby the said journal 60 gear and reel shaft are turned from the first aforesaid gear.

5. An apparatus for dyeing threads and the like, comprising a base, a frame, a dye tank in the said frame, endless chains, means 65 for driving the same in unison, a reel frame pivotally connected to corresponding links of the endless chains, a reel for supporting the material to be dyed, a gear associated with one end of the said reel frame, a rack 70 meshing with the said gear, a journal gear in which one end of the reel shaft is removably connected, a bearing in which the opposite end of the reel shaft is removably journaled, an internal gear connected with the 75 first aforesaid gear, and an intermediate gear meshing both with the said internal gear and journal gear.

6. An apparatus for dyeing threads and the like, comprising a base, a frame, a plurality of dye tanks in the said frame, endless 80 chains, means for driving the same in unison, a reel frame pivotally connected to corresponding links of the endless chains, a reel for supporting the material to be 85 dyed, a shaft for the same, a gear associated with one end of the said reel frame, a rack meshing with the said gear, a journal gear in which one end of the reel shaft is removably connected, a bearing in which the opposite end of the reel shaft is removably journaled, an internal gear connected with the first aforesaid gear, an intermediate gear meshing both with the said internal 90 gear and journal gear, and means for guiding the 95 said reel frames and reels from one into the next succeeding tank through the apparatus.

7. An apparatus for dyeing threads and the like, comprising a base, a frame, a plurality of dye tanks in the said frame, endless 100 chains, means for driving the same in unison, a reel frame pivotally connected to corresponding links of the endless chains, a reel for supporting the material to be dyed, a shaft for the same, a gear associated with 105 one end of the said reel frame, a rack meshing with the said gear, a journal gear in which one end of the reel shaft is removably connected, a bearing in which the opposite end of the reel shaft is removably journaled, means for turning the said journal gear and reel shaft from the aforesaid gear in such a direction that the reel is revolved with the forward portion thereof ascending and the rearward portion descending, and 110 means for guiding the said reel frames and reels from one into the next succeeding tank through the apparatus.

Signed by me this 15th day of October, 1912.

BERNH. TEUFER.
